CARPET SWEEPER OF THE ROTARY DRIVEN BRUSH TYPE

Donald E. Williams, Grand Rapids, Frederick W. Hertzler, Detroit, and Henry T. Lathrop, Grand Rapids, Mich., assignors to Bissell Carpet Sweeper Company, Grand Rapids, Mich.

Application May 21, 1953, Serial No. 356,344

8 Claims. (Cl. 15—45)

This invention relates to improvements in a carpet 15 sweeper of the rotary driven brush type.

The main objects of this invention are:

First, to provide a carpet sweeper which is of relatively small length in proportion to the length of the brush.

Second, to provide a carpet sweeper which is relatively compact and light in weight and at the same time strong and durable, is attractive in appearance, and may be economically produced.

Third, to provide a carpet sweeper provided with a dustpan having a bottom wall which is fixed relative to the casing and having a discharge door at the rear of the casing.

Fourth, to provide a carpet sweeper with a rotatable nonfloating brush and vertically adjustable driving wheels or wheel coating therewith to raise and lower the casing and consequently the brush relative to the surface over which the sweeper is translated.

Objects relating to details and economies of the invention will appear from the description to follow. The invention is defined and pointed out in the claims.

A preferred embodiment of the invention is illustrated in the accompanying drawings, in which:

Fig. 1 is a side elevational view of a sweeper embodying the invention in dust discharging position, the dustpan door being indicated in open position by dotted lines, a portion of the handle and of the casing being partially broken away.

Fig. 2 is a vertical transverse section on a line corresponding to line 2—2 of Figs. 4 and 5.

Fig. 3 is an end elevational view partially in transverse section on a line corresponding to line 3—3 of Fig. 4, the handle being omitted.

Fig. 4 is a plan view with the handle and the casing partially broken away.

Fig. 5 is a bottom view with the handle omitted.

Fig. 6 is a fragmentary view partially in section on a line corresponding to line 6—6 of Fig. 1 showing details of the mounting of the brush.

Fig. 7 is a fragmentary view in section on a line corresponding to line 7—7 of Fig. 3 illustrating details of the adjustment of the carrier for the brush driving wheels.

Fig. 8 is a fragmentary view in section on a line corresponding to line 8—8 of Fig. 1.

In the embodiment of the invention illustrated in the accompanying drawing, the casing designated generally by the numeral 1 comprises a top 2, a bottom 3, front wall 4, rear wall 5, and end walls 6. These walls are constituted or formed by a top unit or member 7 and a bottom unit or member 8 both of generally pan shape, the top member being inverted upon the bottom member, the front, rear and side walls having telescoping engagement at 9. These units or members are desirably formed as sheet metal stampings from aluminum or other desirable material although we contemplate that they may be formed of plastic. The forming of these units or members greatly facilitates and reduces the cost of manufacture and assembling.

2

The bottom member or unit has inward offsets at the rear corner thereof providing wheel housings 10 for the rear floor wheels 11 which are mounted on journals or stub shafts 12 projecting from the end walls. The bottom wall 3 has a brush receiving opening 13 extending between the end walls and transversely of the direction of travel of the sweeper. The portion of the bottom wall at the rear of this opening constitutes the bottom of the dustpan.

10 A dustpan discharge opening 14 is provided in the rear wall and extended into the top of the casing which opening is normally closed by the angled door or closure 15 which fits flush into the walls and is hingedly connected to the top wall by the U-shaped hinge arms 16 pivoted at 17 on brackets 18 secured on the inner side of the top wall as shown in Fig. 2. These hinge members 16 are fixedly secured to the inner sides of the door 15. U-shaped springs 19 are connected at one end to studs 20 on the brackets 18 and at the other end to studs 21 on the hinge members 16. They are so tensioned that they serve to hold the door in both closed and opened positions.

25 The handle 22 is provided with a bail 23 which springably embraces the casing and is pivotally connected thereto by the pivot ears 24 and the pintles 25 on the bail. These pivot ears 24 are located forward of the center of gravity of the casing and the parts carried thereby so that when the sweeper is picked up, as shown in Fig. 1, the sweeper swings to dust discharge position indicated in Fig. 1.

30 The pivot ears are provided with keepers 26 and 27, the bail springably engaging the keepers 27 when the handle is in the position shown in Fig. 1 and with the keepers 26 when the handle is upright. When the handle is disposed at an angle, as is shown in Fig. 2, which is common in sweeping position, it is out of engagement with either keeper so that the sweeper automatically swings to dust discharge position when picked up by the handle and it may be stored in vertically edgewise position as shown in Fig. 1 thus occupying a minimum of space for storage.

35 A brush 28 is of the rotary type consisting of a body or shaft portion 29 in which the tufts 30 are mounted. The brush 28 is rotatably mounted on the journals 31 projecting into bearings 311 provided therefor in the ends of the brush shaft. These journals 31 are carried by supports 32 mounted on the outer sides of the end wall sections of the bottom casing unit with the journals projecting through openings 33 provided therefor into engagement with the brush.

40 The supports 32 in the embodiment illustrated are springable, being secured at one end by the screws 34 and retained in brush engaging position by the bumper 65. As these supports are springable it is only necessary to remove one support. It will be noted that the brush ends are closely adjacent to the end walls which results in utilizing substantially the full length of the sweeper casing. The brush may be introduced and removed through the opening 13 in the casing bottom.

45 The brush is provided with a driven pulley 36 disposed centrally thereof. The floor engaging brush driving wheels 37 and 38 are mounted on the downwardly facing U-shaped wheel carrier 39. The bottom of the casing has an opening 40 extending rearwardly from the opening 13 and surrounded by an upturned flange 41. The wheel carrier 39 is pivoted at 42 to this upturned flange 41. The front end of the wheel carrier is provided with an upwardly projecting bracket 43 having a slot 44 therein engaged by the pin 45 disposed eccentrically on the disc 46 secured to the stem 47 of the grip or finger button 48 which is disposed on the front wall of the casing. This permits the raising or lowering of the wheel carrier relative to the casing and the brush. The sides of the carrier

have slots 49 therein opening to its bottom edges to receive the shaft of the brush with the driven pulley 36 thereof between the walls of the carrier.

The floor engageable driving wheel 37 is provided with a spindle 51 extending through holes 52 provided in the sides of the carrier. These holes are of substantially greater dimensions than the spindle so that the spindle may be floatingly supported by the C-shaped springs 53 which are secured at one end 54 thereof to the wheel carrier and are provided with bearings 55 for the spindle. These springs act to yieldingly urge the driving wheel 50 against the brush pulley 36.

A second or auxiliary driving wheel 38 is provided with a spindle 57 disposed through openings 58 in the wheel carrier and supported by C-shaped springs 59 secured to the carrier at 56 and provided with bearings 60 for the spindle 57. Thus arranged the thrust of the brush driving wheels on the brush pulley is substantially opposed so that the brush may rotate freely without undue load on its journals. The wheels 37 and 38 have some floating movement relative to the brush and casing.

A brush housing member or guard 61 is mounted on the bottom of the casing at the front of the opening 13 therein to overhang the brush and is provided at its rear edge with a downwardly directed comb 62, the teeth of which engage end portions of the bristles rearwardly of the vertical plane of the axis of the brush. This comb is desirably provided with long and short teeth as is shown in Fig. 4, the comb being of the type shown in the application of Werner E. Siebert, Serial No. 260,661, filed December 8, 1951.

At the rear of the brush we provide an upwardly projecting deflector member or guard 63 which constitutes the front wall of the dustpan. The member 63 has a comb 64 on its upper edge. This comb 64 is of the conventional type. A bumper 65 is disposed over the joint between the top and bottom units concealing the same and at the same time serving as a bumper. This bumper is desirably substantially elastic so that it may be pulled out or lifted up for manipulation of the journal supports 32 without the necessity of removing the bumper. By adjustably supporting the driving wheels they may be raised and lowered relative to the brush to adapt the sweeper for use on hard surfaces or surfaces having little pile or nap as well as on surfaces having a relatively deep pile or nap and this adjustment may be very quickly accomplished by means of the finger piece 48 which is on the outside of the casing. The door 15 is provided with a finger hold 66.

The embodiment of our invention illustrated is attractive in appearance, may be economically produced, is relatively light in weight and at the same time is strong and durable. The accumulations in the dustpan may be easily and quickly discharged and the sweeper stored in a vertically upright position as shown in Fig. 1.

We have not attempted to illustrate or describe other embodiments or adaptations of our invention as we believe this disclosure will enable those skilled in the art to embody or adapt our invention as may be desired.

Having thus described our invention, what we claim as new and desire to secure by Letters Patent is:

1. In a carpet sweeper the combination of a casing comprising a top, a bottom, and front, rear and end walls, said top, bottom, front, rear and end walls being constituted by top and bottom members of generally pan shape each integrally formed and having complementary telescopingly engaged front, rear and end wall sections, the bottom member having inset portions at the rear corners thereof providing floor wheel housings and having an elongated brush opening in the bottom wall thereof disposed transversely of the direction of travel of the sweeper, the bottom at the rear of said transverse opening constituting a dustpan, the casing having a discharge opening for said dustpan, a rotary brush disposed in said brush opening and journaled on the end walls of the casing with

its ends closely adjacent to the inner sides thereof, a wheel carrier of downwardly facing channel section pivotally mounted at its rear end on the bottom member of the casing for vertical adjustment relative to said brush, the side walls of said carrier having openings therein through which the brush is disposed, a driven pulley on the brush disposed within said carrier, rear and front floor engageable driving wheels disposed within said carrier and provided with axles, the sides of the carrier having openings floatingly receiving said axles, spring means mounted on said carrier to engage said axles and acting to yieldingly and independently support and to yieldingly urge said driving wheels into driving engagement with said pulley on said brush, means for vertically adjusting said wheel carrier and supporting it in adjusted positions for raising and lowering said driving wheels relative to the brush, and floor wheels mounted within said wheel housings.

2. In a carpet sweeper the combination of a casing comprising a top, a bottom, end walls, and front and rear walls, the bottom having a fixed rear portion constituting a dustpan bottom and having an elongated brush opening therein at the front of said dustpan portion disposed transversely of the direction of movement of the sweeper and a centrally disposed opening which opens to and extends rearwardly from said transverse opening, the bottom having upturned flanges at the edges of said centrally disposed opening, said casing having a dustpan discharge opening at the rear thereof provided with an upwardly swingable closure, a wheel carrier of downwardly facing channel section disposed with its rear end between said upturned flanges on said casing bottom and pivotally mounted thereon, the sides of said wheel carrier being provided with openings extending upwardly from their bottom edges, a rotary brush disposed in said brush opening and comprising a shaft rotatably mounted on the casing end walls and disposed through said openings in the side walls of said wheel carrier and with the ends of the brush closely adjacent to the end walls of the casing, a driven pulley on the brush disposed within the said wheel carrier, a first floor engageable driving wheel disposed within said wheel carrier at the rear of said driven pulley, means on said carrier for yieldably supporting said first driving wheel in driving engagement with said driven pulley, a second floor engageable driving wheel of less diameter than said first driving wheel disposed within said wheel carrier at the front of said driven pulley, means on said carrier for yieldingly supporting said second driving wheel in driving engagement with said driven pulley in opposition to said first driving wheel, and means for adjustably supporting said wheel carrier on its said pivot for raising and lowering said driving wheels relative to the brush.

3. In a carpet sweeper, the combination of a casing comprising a top, a bottom, end walls, and front and rear walls, the bottom having a fixed rear portion constituting a dustpan bottom and having an elongated brush opening therein at the front of said dustpan portion disposed transversely of the direction of movement of the sweeper and a centrally disposed opening which opens to and extends rearwardly from said brush opening, the bottom having upturned flanges at the edges of said centrally disposed opening, said casing having a dustpan discharge opening at the rear thereof provided with an upwardly swingable closure, a wheel carrier of downwardly facing channel section disposed with its rear end between said upturned flanges on said casing bottom and pivotally mounted thereon, the sides of said wheel carrier being provided with openings extending upwardly from their bottom edges, a rotary brush disposed in said brush opening and comprising a shaft rotatably mounted on the casing end walls and disposed through said openings in the side walls of said wheel carrier and with the ends of the brush closely adjacent to the end walls of the casing, a driven pulley on the brush disposed within the said wheel carrier, a floor engageable driving wheel dis-

posed within said wheel carrier at the rear of said driven pulley, means on said carrier for yieldably supporting said driving wheel in driving engagement with said driven pulley, and means for adjustably supporting said wheel carrier on its said pivot for raising and lowering said driving wheel relative to the brush.

4. In a carpet sweeper the combination of a casing comprising a top, a bottom, and front, rear and end walls, said top, bottom, front, rear and end walls being constituted by top and bottom members of generally pan shape formed as integral units and having complementary telescopingly engaged front, rear and end wall sections, the bottom member having a brush opening in the bottom wall thereof, disposed transversely of the direction of movement of the sweeper, the bottom member at the rear of said transverse opening constituting a dustpan, the casing having a dustpan discharge opening at the rear thereof, a rotatably mounted brush disposed in said opening in said bottom member, a driven pulley on the brush, a brush housing member secured to the bottom at the front edge of said transverse opening therein to overhang the brush and having a comb on its rear edge coacting with the brush, a deflector member disposed at the rear of the brush and constituting the front wall of the dustpan and having a comb on its upper edge coacting with the brush, a floor engageable driving wheel drivingly coacting with said pulley on said brush, and rear floor wheels for said casing.

5. In a carpet sweeper the combination of a casing, a rotary brush rotatively mounted in said casing to be raised and lowered therewith, a wheel carrier mounted in said casing centrally thereof relative to the ends of the casing and for vertical adjustment relative to said casing and said brush, said brush being provided with a driven pulley aligned with said carrier, front and rear driving wheels mounted on said carrier in driving engagement with said driven pulley on said brush, means including a grip on the front of the casing and exterior thereof for raising and lowering said carrier and the driving wheels carried thereby relative to the brush, and rear floor wheels coacting with said driving wheels in supporting the sweeper on the surface over which it is translated.

6. In a carpet sweeper the combination of a casing, a rotary brush rotatively mounted in said casing, a wheel carrier mounted in said casing centrally thereof relative to the ends of the casing and for vertical adjustment relative to said casing and said brush, said brush being provided with a driven pulley aligned with said carrier, front and rear driving wheels mounted on said carrier in

driving engagement with said driven pulley on said brush, and means for raising and lowering said carrier and the driving wheels carried thereby relative to the brush.

7. In a carpet sweeper the combination of a casing, a wheel carrier mounted in said casing centrally relative to the ends of the casing and for vertical adjustment, a rotary brush rotatably mounted within the casing, a driven pulley on the brush, a first floor engageable driving wheel yieldably mounted on said wheel carrier at the rear of said driven pulley, a second floor engageable driving wheel yieldably mounted on said wheel carrier at the front of said driven pulley and in driving engagement therewith, said carrier being disposed in overhanging relation to said pulley and driving wheels, means for adjustably supporting said wheel carrier for raising and lowering said driving wheels relative to the brush, and rear floor wheels for said casing.

8. In a carpet sweeper the combination of a casing, comprising top, bottom, front, rear and end walls, said wall portions being constituted by top and bottom units of generally pan shape and having complementary telescopingly engaged front, rear and end wall sections, the bottom unit having inset portions at the rear corners thereof providing floor wheel housings and having a brush opening in the bottom wall thereof extending between the end wall portions, a rotatable brush disposed in said casing with its ends closely adjacent to the end wall portions of said bottom unit, journals for said brush provided with supports mounted on the outer sides of the end wall portions of the bottom unit with the journals projecting therethrough, an elastic bumper strip disposed over and covering the joint between said top and bottom units and extending across the front and ends of the casing in overlying relation to said journal supports, floor wheels mounted within said wheel housings, and a floor engageable brush driving wheel disposed between the casing end walls and drivingly associated with said brush.
